UNITED STATES PATENT OFFICE

DON E. DASHER, OF HARRISON TOWNSHIP, NEAR DAYTON, MONTGOMERY COUNTY, OHIO, ASSIGNOR TO TRUPAR MANUFACTURING COMPANY, OF DAYTON, OHIO, A CORPORATION OF OHIO

DESIGN FOR AN AIR CONDITIONING PEDESTAL FAN

Application filed March 17, 1933. Serial No. 47,495. Term of patent 14 years.

To all whom it may concern:

Be it known that I, DON E. DASHER, a citizen of the United States, residing in Harrison Township, near the city of Dayton, in the county of Montgomery and State of Ohio, have invented a new, original, and ornamental Design for Air Conditioning Pedestal Fans, of which the following is a specification, reference being had to the accompanying drawing, forming part thereof.

Figure 1 is a perspective view, and Figure 2 is a view looking down on top of an air conditioning pedestal fan on a reduced scale, showing my new design.

I claim:

The ornamental design for an air conditioning pedestal fan, as shown and described.

DON E. DASHER.
